BASEBOARD RADIATOR HOUSING

Abraham B. Chadwick, Fern Creek, Ky., assignor to American Radiator & Standard Sanitary Corporation, New York, N. Y., a corporation of Delaware

Application July 21, 1955, Serial No. 523,543

6 Claims. (Cl. 98—40)

This invention relates to new and useful improvements in radiator enclosures and more particularly to a damper control for a baseboard-type radiator housing to control the heat supplied thereby.

Modern heating systems often employ heating elements which are run along room walls and which are surrounded by suitable radiator enclosures. These radiator enclosures provide heat directing means and also preferably include a heat control means such a damper which can control the flow of air through the radiator.

Presently known heat controls or dampers for radiator housings have proven to be unsatisfactory for several reasons. Those of simple construction have proven to be poorly controlled, noisy, and erratic in adjustment. Quieter and more positively operated ones have proven to be complicated and difficult to install and maintain. Therefore a need has existed for a simple, inexpensive and easily installed heat control or damper suitable for use with radiator enclosures and which can be economically used with both short installations and with the modern elongated baseboard-type installations.

An object of the invention is to provide a damper control of simple construction.

Another object is to provide a damper which is supported by the radiator enclosure.

Another object is to provide a damper having an accessible control means which will remain in any desired position of adjustment.

Another object is to provide a damper which may be readily installed in a baseboard-type radiator housing.

Another object is to provide a damper readily controllable for any degree of opening between fully closed and fully open positions.

The invention consists in the improved construction and combination of parts to be more fully described hereinafter and the novelty of which will be particularly pointed out and distinctly claimed.

In the accompanying drawings to be taken as a part of this specification, there is fully and clearly illustrated a preferred embodiment of the invention, in which drawings:

Fig. 1 is a view in front elevation of a baseboard radiator having the invention and with certain parts broken away to show internal construction;

Fig. 2 is a view in section on the line 2—2 of Fig. 1 taken in the direction of the arrows; and

Fig. 3 is a view in section on the line 3—3 of Fig. 2 showing the slider mechanism.

Referring to the drawings by characters of reference, 1 designates a rear panel of a baseboard radiator enclosure adapted to seat against a room wall and having at its bottom edge a longitudinally extending foot portion 2 adapted to seat on the floor of the room. At its upper end the panel 1 has a forwardly extending top wall 3 which terminates at its forward edge in a downwardly and rearwardly bent hook portion or channel 4. Secured to rear wall 1 there is a plate-like support-

2

ing member or reinforcing angle 5 having forwardly extending flange 6 which terminates at its upper end in a supporting portion 7 on which the top wall 3 seats. At its lower end the flange 6 has a forwardly extending arm 8 which terminates in an upwardly extending hook portion 9. Releasably supported on the arm 8 and seating behind the hook portion 9 there is a front panel 10, which at its lower edge has an up-turned channel 11 releasably held by a down-turned resilient hook on the end of bracket 12. Extending longitudinally within the lower portion of the housing there is a fin-type radiator 13 which is supported by hook members 14 carried by brackets 15 extending from the supporting members 5.

15 Extending longitudinally of the housing above the radiator 13 there is a damper member 16 having a plurality of longitudinal spaced cutout portions or openings 17 through which the arms 8 respectively extend. The damper member 16 is thus supported by the upper edge of the openings 17 upon the arms 8 for rotary or pivotal movement. Secured on the rear or lower edge of the damper member 16 there is a clip or bracket 18 having an outward extending arm 19 which is apertured to receive a pin 20. Secured to the pin 20 is one end 25 of the operating member 21, which in the preferred embodiment is a flexible member such as a flexible bead chain. The other end of the operating member or chain 21 is connected to a pin 22 extending through an aperture in a slider arm 23. The slider arm 23 is secured 30 by welding or the like to the under face of a rectangular slide member 24 which is guided for reciprocal sliding movement in the front and rear side channels 25, 26 of a supporting plate 27. The side channels 25, 26 are formed by bending over the front and rear edges of the plate 27. The supporting plate 27 is of resilient sheet metal and is bent upward along its longitudinal center line so that it is mounted on the top wall 3 by being resiliently held under compression and snapped between the inner end of the hook portion 4 and the corner 40 formed by the juncture of the panel 1 and the top wall 3. Stops 34, punched or otherwise suitably formed in both ends of the supporting plate 27, limit the travel of the slide member 24 to the portion of the supporting plate 27 therebetween. The arm 23 has a downward 45 extending front end portion 28 to which a finger grip knob 29 is secured.

The damper 16 is pivotally mounted on the arm 8 of bracket 5 so that it swings about a longitudinal axis offset from its longitudinal center line. One side of 50 the damper is thus heavier and it swings downwardly so that the damper normally is held open by gravity. The clip 18 is fixedly secured to the damper 16 and is restricted to motion in a vertical arc by the pivotal mounting of the damper 16. The other end of the chain 55 21 attached to the pin 22 can only move in a horizontal plane due to the horizontal path of slide member 24. In Fig. 1 the chain 21 is shown vertically disposed with the damper 16 open. When the knob 29 is moved to the left, as shown in dot-dash lines, the effective vertical length of the cable is shortened and hence the lower side of the damper 16 is raised or swung upwardly to move it toward its closed position.

The friction between slide member 24 and its supporting plate 27 is sufficient to hold slide member 24 in any 60 position between end stops 34. The lateral pull when the lower side of the damper 16 is raised, occasioned by the inclined position of the chain 21, adds to this friction and tends to hold the slide in position. Thus, the damper 16 may be left in any position desired. The weight of the lower side of the damper is sufficient to open it when the knob 29 is shifted to the right. If desired, the lower side of the damper may be weighted.

to make this action more positive or a suitable spring may be utilized for biasing it.

Extending upward from each of the arms 8 there is a supporting finger 30 which forms, with the flanges 6, upwardly open slots 31. Extending longitudinally of the housing and positioned in the slots 31 is the substantially vertical flange 32 of an air splitter member which has its other flange 33 extending forward and upward so that it rests upon the top ends of the fingers 30. The flange 32 is preferably bent longitudinally on a horizontal line so that it engages the front and rear walls of the slots 31 so as to tension the flange 32 and hold the splitter member tightly in position.

The operation of the damper member is as follows: The damper is shown in solid lines in its open or generally vertical position and in dash-dot lines (Figs. 1 and 2) in its closed position with the lower edge engaging the lateral flanges of the supporting members 5 which serve as stops to limit the closing movement of the damper 16. When it is desired to move the damper from its open to its closed position, the slider knob 29 is moved laterally from right to left (Fig. 1), causing the chain or member 21 to raise the lower edge of the damper 16 to thereby pivot the damper 16 to its closed position, as shown in dash-dot lines in Fig. 2. Sliding the knob 29 to the right lowers the end of chain 21 fastened to the clip 18, allowing the damper 16 to swing by gravity toward its open or vertical position. When the chain 21 is in substantially vertical position, the damper 16 will be in substantially full open position. The slider knob 29 may be moved to any desired position intermediate its extreme positions to provide for a partial opening of the damper 16 as desired.

It will be seen that the present invention provides an improved baseboard-type radiator housing having an improved damper. The damper is supported by the radiator enclosure and has a simple, smooth-acting, quiet control which adjusts the damper for any desired degree of opening between fully closed and fully open positions. The improved damper control is adapted for all sizes of dampers, both long or short and narrow or wide. The damper controls can be readily located where desired along the radiator installation without requiring changes in the radiator assembly, as the damper control is adapted for positioning at any point of a radiator panel. The damper control is also adapted to be accessible so that the user may readily manipulate and observe the position of the damper control.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. In a baseboard radiator enclosure, a housing having a rear wall and having a top wall with a downwardly and rearwardly turned channel along its front edge, a guide member resiliently held at its front and rear edges in said channel and at the juncture of said rear and top walls, respectively, said guide member having channels at its front and rear edges, a slider having its front and rear edges extending into and guided in said guide member channels, an operating arm secured to said slider, a bracket secured to said rear wall and having a forwardly extending supporting arm, a damper pivoted on said supporting arm, and an operating member connecting the lower edge of said damper and said slider member so that lateral sliding of said operating arm will rotate said damper.

2. In a baseboard radiator enclosure, a housing having a rear wall and a top wall with a downwardly and rearwardly turned channel along its front edge, a guide member resiliently held at its front and rear edges in said channel and at the juncture of said rear and top

walls, respectively, said guide member having channels at its front and rear edges, a rectangular slider member having its front and rear edges extending into and slideable in said guide member channels, an operating arm secured to said slider member and extending from the front toward the rear of said housing, a bracket member secured to said rear wall and having a forwardly extending supporting arm, a damper member pivoted on said supporting arm, a clip member secured to the lower edge of said damper member, and a flexible member connecting said clip member and said slider member so that lateral sliding of said operating arm will rotate said damper member.

3. In a baseboard radiator enclosure, a housing having a rear wall, a top wall with a downwardly and rearwardly turned channel along its front edge and a front panel, said rear wall and said front panel comprising a heat directing channel, a guide member resiliently held at its front and rear edges in said channel and at the juncture of said rear and top walls, respectively, said guide member having channels at its front and rear edges, a slider member having its front and rear edges extending into and slideable in said guide member channels, an operating arm secured to said slider member and extending from the front toward the rear of said housing, a bracket member secured to said rear wall and having a forwardly extending supporting arm, a damper member pivoted on said supporting arm between said rear wall and said front panel where it is movable between an open position along the heat directing channel to a closed position thereacross, a clip member secured to the lower edge of said damper member, and a flexible member connecting said clip member and said slider member so that lateral sliding of said operating arm will move said damper member.

4. A housing having a rear wall and a top wall extending forwardly from said rear wall, a supporting member extending forwardly from said rear wall below said top wall, a front wall spaced from said rear wall and having its top edge spaced from said top wall to provide an outlet opening from the space between said front and rear walls, the forward portion of said top wall having a downward and rearward extending portion forming a rearwardly open channel, a resilient supporting plate having upwardly diverging front and rear portions, said front portion having a downward and rearward projecting edge portion forming a channel seating in said rearwardly open channel, said rear portion having a downward and forward projecting edge portion forming a forward facing channel and seating in the angle between said rear and said top walls, said supporting plate having its said front and rear portions flexed toward each other and frictionally held in position relative to said top wall, a rectangular slider member having its front and rear edges positioned and guided respectively in said supporting plate channels, means for shifting said slider member along said supporting plate, a damper member fulcrumed on said supporting member to swing on an axis parallel to said rear wall, and means interconnecting said slider member and said damper member so that shifting of said slider member will move said damper member.

5. A housing having a rear wall and a top wall extending forwardly from said rear wall, a supporting member extending forwardly from said rear wall below said top wall, a front wall spaced from said rear wall and having its top edge spaced from said top wall to provide an outlet opening from the space between said front and rear walls, the forward portion of said top wall having a downward and rearward extending portion forming a rearwardly open channel, a resilient supporting plate having upwardly diverging front and rear portions, said front portion having a downward and rearward projecting edge portion forming a channel seating in said rearwardly open channel, said rear portion having a downward and forward projecting edge portion forming a

forward facing channel and seating in the angle between said rear and said top walls, said supporting plate having its said front and rear portions flexed toward each other and frictionally held in position relative to said top wall, a rectangular slider member having its front and rear edges positioned and guided respectively in said supporting plate channels, a slider arm secured to said slider member and operable to slide said slider member in said supporting plate channels, a damper member fulcrumed on said supporting member to swing on an axis parallel to said rear wall, a clip member secured to the lower edge portion of said damper member, and a flexible connecting member joining said clip member to said slider arm so that shifting of said slider arm will move said damper member.

6. A housing having a rear wall and a top wall extending forwardly from said rear wall, a plurality of laterally spaced plate-like supporting members extending forwardly from said rear wall and engaging the underside of said top wall to support the same and each having a forwardly extending arm, a front wall spaced from said rear wall and having its top edge spaced from said top wall to provide an outlet opening from the space between said front and rear walls, the forward portion of said top wall having a downward and rearward extending portion forming a rearwardly open channel, a resilient support-

ing plate having upwardly diverging front and rear portions, said front portion having a downward and rearward projecting edge portion forming a channel seating in said rearwardly open channel, said rear portion having a downward and forward projecting edge portion forming a forward facing channel and seating in the angle between said rear and said top walls, said supporting plate having its said front and rear portions flexed toward each other and frictionally held in position relative to said top wall, a rectangular slider member having its front and rear edges positioned and guided respectively in said supporting plate channels, means for shifting said slider member along said supporting plate, a damper member having a plurality of apertures therethrough, each said aperture receiving one of said arms so that said damper member is fulcrumed on said supporting member, and means interconnecting said slider member and said damper member so that shifting of said slider member will move said damper member.
